UNITED STATES PATENT OFFICE.

CHARLES MATTHEWS MANLY, OF FREEPORT, NEW YORK.

PUMP OR MOTOR CYLINDER, AND METHOD OF MAKING THE SAME

1,075,486

Specification of Letters Patent.

Patented Oct. 14, 1913.

Original application filed July 19, 1911, Serial No. 629,464. Divided and this application filed January 23, 1913. Serial No. 744,749.

To all whom it may concern:

Be it known that I, CHARLES MATTHEWS MANLY, a citizen of the United States, residing at Freeport, Long Island, New York, 5 have invented a new and useful Improvement in Pump or Motor Cylinders and Methods of Making the Same, of which the following is a specification.

This application relates to pump or motor 10 cylinders and methods of making the same, and constitutes a division of my prior application, Serial No. 629,464, filed July 19, 1911.

The particular mechanism forming the 15 subject matter of my original application is a hydraulic variable speed gear comprising a pump and a motor having a closed fluid connection whereby the motor is driven by the fluid pressure generated in 20 the pump. In machines of this character weight is a feature of prime importance, and in order to keep the weight down it is desirable to use material of high tensile strength for the parts which withstand the 25 fluid pressure. To that end each cylinder with its attached valve chamber is made of a single billet of forged steel, the top of the cylinder being connected to the middle port of the valve chamber by a curved 30 passageway to permit ingress and egress of the fluid.

The subject matter of the present application includes the one piece cylinder and valve chamber as an article of manufacture, 35 and the novel, expeditious and inexpensive method of making the same, as will be fully described in the following specification and pointed out in the appended claims.

In the accompanying drawings I have 40 illustrated my improved structure in various stages of its manufacture, and in the said drawings,

Figure 1 represents in side elevation the solid billet as it comes from the forging 45 press; Fig. 2 is a sectional view on line 2-2 of Fig. 1 after the connecting passage between the cylinder and valve chamber has been bored; Fig. 3 is a longitudinal sectional view of the bored cylinder with the 50 attached valve chamber before the bending operation; Fig. 4 is a similar view of the completed article showing the part in a convenient form of bending apparatus, and. Fig. 5 is a side elevation view of the article 55 showing a modified step in the process.

The solid billet comprising the cylinder portion 1, the part 2 forming the valve chamber parallel with the cylinder portion and the straight connecting web 3 perpendicular to the cylinder and valve chamber 50 is forged in any suitable press to the shape shown in Fig. 1. In addition to the essential elements of the billet above noted it preferably comprises a projection 4 in line with the web 3, a flange 5 along the outer 55 side wall of the valve chamber and flanges 6 and 7 around the lower ends of the cylinder and valve chamber portions respectively. The web 3 is then bored to form the passage 8, the bore being started 70 through the projections 4 on the cylinder portion, and the parts 1 and 2 are bored as shown in Fig. 3. The next step in the process of manufacture is preferably the bending of the bored web 3. This may be accomplished in various ways. As shown in Fig. 4 after first heating the web 3 to the desired bending temperature, the valve chamber is clamped on a mandrel 9 between suitable supports 10 and the cylinder mounted on 80 a mandrel 11 carried by parallel links 12 and 13 having their pivots on a line parallel with the axial line of the clamped valve chamber. The link 13 is provided with an integral extension 14 to which power may 85 be applied in the direction of the arrow, thereby moving the cylinder toward the valve chamber and at the same time outward to effect the desired bend, the length of the links 12 and 13 determining the ratio 90 of the lateral and longitudinal movements. After the web 3 has cooled, the element is completed by counter-boring the valve and cylinder ports as shown in dotted lines in Fig. 4, boring the intake and delivery ports 95 15, 16, reducing and threading a portion of the flanges 6 and 7 to form suitable connections with the crank chamber of the motor, and threading the ends of the cylinder, valve chamber and passage 8 for the 100 reception of suitable closure caps, or plugs.

It is of course not essential that the various steps be performed in the order set forth. The entire machining may be completed before the bending is effected, or the 105 bending operation may be performed immediately after the passage 8 is bored as indicated in Fig. 5, suitable external clamps being substituted for the mandrels 9 and 11. Further, the heating and bending may be 110

simultaneously performed, that is, the bored passage may be kept heated to its bending temperature throughout the bending operation. Any suitable means may be employed for this purpose as for instance gas torches on the bending table directed against the bored passage-way. Unless the bending operation is performed quite rapidly the metal of the passage-way has to be highly heated in order not to cool below the necessary temperature before the bend is finished. This hurried work may result in uneven bends which, with excessive heat, may weaken the walls of the passage-way. This contingency is entirely removed by heating the portion to be bent in the manner described, the intensity of the heat at different points being adjusted to properly meet the variations of thickness and curvature of the part.

The advantages of the curved passage-way over the straight connection will be immediately apparent from a comparison of Figs. 3 and 4. The overall dimension of the motor is reduced by reducing the height of the valve chamber to substantially that of the cylinder and the weight of the entire motor is reduced by permitting a smaller crank case at the valve chamber connection without prolonging the length of the valve chamber. Were the billet forged with the web 3 curved it would be impossible to bore a passage through the same. The metal would have to be machined away with small tools, a process so slow and expensive as to more than offset the advantages of the curved connection. By my novel process the

curved passage article can be made quite as cheap as the straight passage type, the metal saved in the crank case or valve chambers more than off-setting the cost of the simple bending operation.

Claims:—

1. As a new article of manufacture, a forged steel cylinder and valve chamber connected by an integral bored passage-way. 45

2. As a new article of manufacture, a forged steel cylinder and valve chamber connected by an integral bored passage-way, said passage-way extending from the top of the cylinder to a point on the valve chamber offset therefrom. 50

3. A pump or motor cylinder comprising a forged steel bored cylinder with a side port at its outer end, a forged steel bored valve chamber parallel with said cylinder 55 and connected therewith by an integral curved passage way connecting said end port of the cylinder with a middle port of the valve chamber, the said passage way being bored and having a configuration resulting 60 from boring the passage way while straight and subsequently curving the same by bending.

In testimony, whereof, I have signed my name to this specification in the presence of 65 two subscribing witnesses, this 22nd day of January 1913.

CHARLES MATTHEWS MANLY.
